US0D1028523S

(12) **United States Design Patent** (10) **Patent No.:** **US D1,028,523 S**
(45) **Date of Patent:** **** May 28, 2024**

(54) **HAIR CARE ACCESSORY**

- (71) Applicant: **SharkNinja Operating LLC**, Needham, MA (US)
(72) Inventors: **Daniel Van Alphen**, Lexington, MA (US); **Ramsey Lehman**, Brookline, MA (US)
(73) Assignee: **SharkNinja Operating LLC**, Needham, MA (US)

(**) Term: **15 Years**

(21) Appl. No.: **29/922,875**

(22) Filed: **Dec. 26, 2023**

Related U.S. Application Data

- (63) Continuation of application No. 29/841,056, filed on Jun. 2, 2022, now Pat. No. Des. 1,021,238.
(51) **LOC (14) Cl.** **28-03**
(52) **U.S. Cl.** **D4/100; D4/134**

CLAIM

The ornamental design for a hair care accessory, as shown and described.

DESCRIPTION

FIG. 1 is a front perspective view of an embodiment of a brush accessory that can be used with a hair care appliance; FIG. 2 is a front view of the brush accessory of FIG. 1; FIG. 3 is a back view of the brush accessory of FIG. 1; FIG. 4 is a left side view of the brush accessory of FIG. 1; FIG. 5 is a right side view of the brush accessory of FIG. 1; FIG. 6 is a top view of the brush accessory of FIG. 1; FIG. 7 is a bottom view of the brush accessory of FIG. 1; and, FIG. 8 is a front perspective view of the brush accessory of FIG. 1 shown mated to the hair care appliance. The broken lines shown in all of the drawing figures illustrate environmental structure and form no part of the claimed design. The dash-dot broken lines represent boundary lines that form no part of the claimed design.

1 Claim, 5 Drawing Sheets
